CLAIM

The ornamental design for a pill dispenser, as shown and described.

DESCRIPTION

1. Pill dispenser

1.1 is a front elevation view of a pill dispenser embodying my new design;

1.2 is a left side elevation view thereof;

1.3 is a rear elevation view thereof;

1.4 is a right side elevation view thereof;

1.5 is a top plan view thereof;

1.6 is a bottom plan view thereof;

1.7 is a front perspective view thereof; and

1.8 is a rear perspective view thereof.

The broken lines in the reproductions illustrate portions of the pill dispenser other than packaging that form no part of the claimed design.
